MOUNTING MEANS FOR CONTACT MEMBERS

Charles J. Mahler, Snyder, and Marshall P. White, Cheektowaga, N. Y., assignors to Westinghouse Electric Corporation, East Pittsburgh, Pa., a corporation of Pennsylvania

Application April 4, 1957, Serial No. 650,693

7 Claims. (Cl. 200—166)

Our invention relates, generally, to mounting means for contact members and, more particularly, to spacers for auxiliary contact members of switching devices and relays.

Auxiliary contact members provided on relays and switching devices are usually of two types, normally open or front contacts and normally closed or back contacts. A device may be supplied with one or more sets of each type of contacts depending on the requirements of the system in which it is utilized. It is desirable that the auxiliary contacts be so mounted that they can be readily changed from one type to the other to meet the requirements of the system in which the device is utilized.

A copending application of C. J. Mahler, M. P. White, and R. B. Immel, Serial No. 623,566, filed November 21, 1956, describes a means for mounting auxiliary contact members which permits them to be readily changed from one type to another type. In the structure disclosed in the aforesaid application a bridging member, which spans a pair of stationary spaced contact members, is reversibly mounted on a guide member composed of a resilient material and having a bifurcated end which extends through an opening in the cross bar of a contactor. The prongs of the guide member have projections on their outer edges which engage the cross bar at the bottom of the opening to secure the guide member in the cross bar. The bridging member may be reversed to change from a normally open to a normally closed type of auxiliary contact, or vice versa, by interchanging a spacing sleeve and a spring on the guide member.

An object of our invention is to provide an improved spacer for utilization on a contact guide member.

Another object of our invention is to provide a spacer for a contact guide member which is self-locking on the guide member.

A further object of our invention is to provide a contact assembly having a bridging member, a spacer and a spring which may be readily changed on a guide member to provide either a normally closed assembly or a normally open assembly.

Other objects of our invention will be explained fully hereinafter or will be apparent to those skilled in the art.

In accordance with one embodiment of our invention, a generally cylindrical spacer for a contact assembly is preferably molded from nylon and has a groove across the diameter at one end of the cylinder. Two diametrically opposed spherical projections are molded on the inside of the spacer near the end having the groove. The guide member on which the contact assembly is mounted has two spherical depressions on each side or a total of four depressions. The resilient property of the nylon and the groove in the spacer permit the spacer to be pushed on the guide until the projections on the spacer snap into one pair of the depressions in the guide, thereby retaining the spacer on the guide. When the spacer is reversed to change the contact assembly from normally open to normally closed, or vice versa, the projections

2

on the spacer engage the other pair of depressions in the guide.

For a better understanding of the nature and objects of our invention, reference may be had to the following detailed description, taken in conjunction with the accompanying drawing, in which:

Figure 1 is a view, in left elevation, of a portion of a switching device and showing a normally open contact assembly embodying the principal features of the invention;

Fig. 2 is a view, in front elevation of the switching device and showing normally open and normally closed contact assemblies;

Fig. 3 is a view, in right elevation, of the switching device and showing a normally closed contact assembly;

Fig. 4 is an enlarged view, partly in section and partly in front elevation, of a contact guide and a spacer provided for a normally open contact assembly;

Fig. 5 is an enlarged view, partly in section and partly in side elevation, of the contact guide and the spacer for a normally closed contact assembly;

Fig. 6 is an enlarged view, in top plan, of the spacer;

Fig. 7 is an enlarged view, in section, taken along the line VII—VII in Fig. 6;

Fig. 8 is an enlarged view, in bottom plan, of the spacer, and

Fig. 9 is an enlarged view, in bottom plan, of the contact guide member.

Referring to the drawing, and particularly to Fig. 1, the normally open auxiliary contact assembly shown therein comprises a carrier or cross bar 11, a pair of spaced stationary contact members 12 and 13 which may be mounted on a relay or contactor 10, only a portion of which is shown, a bridging member 14 having contact members 15 and 16 thereon for engaging the stationary contact members 12 and 13, respectively, a guide member 17 for supporting the bridging member 14, and a spacing sleeve 18 and a spring 19 disposed on the guide member 17 at opposite sides of the member 14.

The carrier on cross bar 11 may be molded from any suitable insulating material, and it may be utilized for supporting main contact members of the relay or contactor as well as other auxiliary contact members in addition to those shown. The carrier 11 may be attached to actuating means (not shown) for the contactor in any suitable manner. Thus, the auxiliary contact members are actuated in conjunction with the main contact members of the relay or contactor.

As shown, a recess 22 is provided in one corner of the carrier 11. A raised portion 23 is provided on the top of the carrier 11 over the recess 22. As described in the aforesaid copending application, a generally rectangular opening extends through the raised portion 23 into the recessed portion 22 of the carrier 11. As shown most clearly in Figs. 4 and 5, the contact guide member 17 has a generally rectangular portion 24 which is disposed in the opening in the carrier 11. The lower end of the guide 17 is bifurcated and each prong 25 has an angularly disposed

projection 26 thereon. The upper surface of the projection 26 is preferably at an angle of approximately 30° to the surface of the carrier 11 which it engages at the bottom of the opening in the carrier. The guide 17 has a shoulder 27 which engages the top surface of the raised portion 23 at the top of the opening in the carrier. Thus, the guide member 17 is wedged in the opening and is held securely in place.

The guide member 17 is preferably molded from nylon which, in addition to being a good electrical insulator, also has exceptional wearing qualities and resilience. The resilient property of nylon is utilized to secure the locking action to retain the guide member in the carrier 11. If it

is desired to remove the guide member 17, it may be forced upwardly by means of a suitable tool.

As shown more clearly in Figs. 4 and 5, the guide member 17 has an integrally formed head 28 on its upper end. As shown in Fig. 1 the spacing sleeve 18 is disposed on the guide member between the head 28 and the bridging member 14 which is slidably disposed on the guide member. The spring 19 is disposed on the guide member between the bridging member 14 and the top surface of the raised portion 23 of the carrier 11. When the carrier 11 is moved vertically, the contact members 15 and 16 engage the stationary contact members 12 and 13, respectively, and the spring 19 is compressed to maintain a predetermined contact pressure between the contact members.

The contact assembly shown in Fig. 3 is of the normally closed type. It is similar in structure to the assembly shown in Fig. 1. However, the bridging member 14 is reversed and placed above the stationary contact members 12 and 13. The spacing sleeve 18 and the spring 19 are interchanged, the spring 19 being between the bridging member 14 and the head 28 of the guide 17, and the spacing sleeve 18 being between the bridging member and the raised portion 23 of the carrier 11. The contact members 15 and 16 engage the contact members 12 and 13, respectively, when the carrier 11 is in its lowermost portion and are disengaged from the contact members 12 and 13 when the carrier 11 is raised vertically by the actuating means of the contactor.

As explained in the aforesaid copending application, the contact assembly may be changed from one type to the other by reversing the bridging member 14 and interchanging the spacer 18 and the spring 19. Thus, the contact assemblies may be changed after the device is originally assembled and installed by removing the guide member 17 from the carrier 11, reversing the bridging member and interchanging the spacer and the spring, and then reinserting the guide member 17 in the carrier.

In order to prevent the spacer from sliding up and down on the guide during contact operation and also to prevent the contact assemblies from becoming disassembled after they are assembled in the desired relation, it is desirable to provide a means for retaining the spacing sleeve 18 in its correct position on the guide 17. As shown, the spacer 18 is generally cylindrical in shape and is preferably molded from nylon which, as explained hereinbefore, is a good insulator and has exceptional wearing qualities and resilience. As shown most clearly in Figs. 6 and 7, the sleeve 18 has a diametrically disposed groove 31 across one end. The groove 31 extends partway up the length of the sleeve 18. Two oppositely disposed spherical projections 32 are molded on the inside of the spacer 18 near the end having the groove 31. The guide member 17 has two spherical depressions 33 molded on each side making a total of four depressions in all.

The spacer 18 may be installed on the guide 17 by pushing the spacer onto the guide, thereby forcing the groove 31 to open slightly. The spacer is pushed onto the guide until the spherical projections 32 on the spacer engage one pair of the spherical depressions on the guide 17. The resilient property of the nylon, or other resilient material, causes the projections to snap into the depressions, thereby retaining the spacer in position.

As shown in Figs. 1 and 4, when the contact assembly is of the normally open type, the spacer 18 is disposed at the top of the contact guide 17 and the projections 32 on the spacer engage the top pair of depressions 33 in the guide 17. The spring 19 is disposed below the bridging member 14.

As shown in Figs. 3 and 5, when the contact assembly is of the normally closed type, the spacer 18 is disposed below the bridging member 14 and the projections 32 on the spacer engage the lower pair of depressions 33 in the contact guide 17. It will be noted that, as shown in Fig. 5, the spacer 18 is turned end for end from the position

shown in Fig. 4. The spring 19 is disposed above the bridging member 14 as shown in Fig. 3.

As previously explained, a contact assembly may be readily changed from one type to the other by reversing the bridging member 14 and interchanging the positions of the spacer 18 and the spring 19. The resiliency of the material of which the spacer 18 is composed permits the spacer to be removed from the guide 17. As previously explained, the resiliency of the material of which the guide 17 is composed permits the guide to be removed from the carrier 11 in order to make the desired change in the contact assembly. However, the spacer 18 is normally retained in its correct position on the guide 17 by means of the projections 32 and the depressions 33, thereby preventing the spacer from sliding on the guide during contact operation and also preventing these members from becoming separated.

From the foregoing descriptions, it is apparent that we have provided an inexpensive, simple and effective means 20 of retaining the members of a contact assembly together. The elimination of small parts and screws reduces the time required to assemble the members and also reduces the space required for the contact assembly when it is installed on an electrical device. Furthermore, the apparatus 25 is safer electrically since the insulation and creepage distance between live parts of the assembly is increased.

Since numerous changes may be made in the above-described construction, and different embodiments of the 30 invention may be made without departing from the spirit and scope thereof, it is intended that all matter contained in the foregoing description or shown in the accompanying drawing shall be interpreted as illustrative and not in a limiting sense.

35 We claim as our invention:

1. In a contact assembly, in combination, a pair of spaced stationary contact members, a bridging member having spaced contact members thereon for engaging said stationary contact members, a movable carrier, a guide member removably mounted on the carrier, said bridging member being reversibly mounted on the guide member, a spring removably mounted on the guide member at one side of the bridging member, a separate generally cylindrical spacer disposed on the guide member at the other side of the bridging member, a projection on the spacer frictionally engaging the guide member to removably retain the spacer on the guide member, and said spring and said spacer being interchangeable in position on the guide member when the bridging member is reversed.

40 2. A contact supporting means comprising a movable carrier, a guide member removably mounted on the carrier, a bridging contact member reversibly mounted on the guide member, a coil spring disposed on the guide member at one side of the bridging member, a separate generally cylindrical spacer disposed on the guide member at the other side of the bridging member, said spacer having an internal projection thereon frictionally engaging the guide member to releasably retain the spacer at a predetermined position on the guide member, and said spring and said spacer being interchangeable in position on the guide member when the bridging member is reversed.

45 3. A contact supporting means comprising a movable carrier, a guide member removably mounted on the carrier, a bridging contact member reversibly mounted on the guide member, a coil spring disposed on the guide member at one side of the bridging member, a generally cylindrical spacer disposed on the guide member at the other side of the bridging member, said spacer being composed of a resilient material and having a groove across one end, an internal projection on the spacer near the grooved end, said projection frictionally engaging the guide member to releasably retain the spacer at a predetermined position on the guide member, and said spring

50 4. A contact supporting means comprising a movable carrier, a guide member removably mounted on the carrier, a bridging contact member reversibly mounted on the guide member, a coil spring disposed on the guide member at one side of the bridging member, a generally cylindrical spacer disposed on the guide member at the other side of the bridging member, said spacer being composed of a resilient material and having a groove across one end, an internal projection on the spacer near the grooved end, said projection frictionally engaging the guide member to releasably retain the spacer at a predetermined position on the guide member, and said spring

and said spacer being interchangeable in position on the guide member when the bridging member is reversed.

4. A contact supporting means comprising a movable carrier, a guide member removably mounted on the carrier, a bridging contact member reversibly mounted on the guide member, a coil spring disposed on the guide member at one side of the bridging member, a generally cylindrical spacer disposed on the guide member at the other side of the bridging member, said spacer being composed of a resilient material and having a groove across one end, an internal projection on the spacer near the grooved end, a depression in the guide member, said projection being biased into said depression by the resiliency of the spacer to releasably retain the spacer at a predetermined position on the guide member, and said spring and said spacer being interchangeable in position on the guide member when the bridging member is reversed.

5. A contact supporting means comprising a movable carrier, a guide member removably mounted on the carrier, a bridging contact member reversibly mounted on the guide member, a coil spring disposed on the guide member at one side of the bridging member, a generally cylindrical spacer disposed on the guide member at the other side of the bridging member, said spacer being composed of a resilient material and having a groove across one end, an internal projection on the spacer near the grooved end, at least two depressions in the guide member spaced longitudinally of the guide member, said projection being disposed in one of said depressions when the spacer is on one side of the bridging member, and said projection being in another one of said depressions when the bridging member is reversed and the spacer and the spring are interchanged in position on the guide member.

6. A contact supporting means comprising a movable carrier, a guide member removably mounted on the carrier, a bridging contact member reversibly mounted on the guide member, a coil spring disposed on the guide

member at one side of the bridging member, a generally cylindrical spacer disposed on the guide member at the other side of the bridging member, said spacer being composed of a resilient material and having a diametrical- 5 ly disposed groove across one end, oppositely disposed internal projections on the spacer near the grooved end, two pairs of oppositely disposed depressions in the guide member spaced longitudinally of the guide member, said projections being disposed in one pair of said depressions when the spacer is on one side of the bridging member, and said projections being in the other pair of depressions when the bridging member is reversed and the spacer and the spring are interchanged in position on the guide member.

10 7. In a contact assembly, in combination, a pair of spaced stationary contact members, a bridging member having spaced contact members thereon for engaging said stationary contact members, a movable carrier, a guide member removably mounted on the carrier, said bridging member being reversibly mounted on the guide member, a coil spring disposed on the guide member at one side of the bridging member, a generally cylindrical spacer disposed on the guide member at the other side of the bridging member, said spacer being composed 15 of a resilient material and having a groove across one end, an internal projection on the spacer near the grooved end, at least two depressions in the guide member spaced longitudinally of the guide member, said projections being disposed in one of said depressions when the spacer is on one side of the bridging member, and said projection being in another one of said depressions when the bridging member is reversed and the spacer and the spring are interchanged in position on the guide member.
